AIRBORNE GUN SIGHT OF THE "OWN SPEED" TYPE

Edmund B. Hammond, Jr., Brooklyn, and Ervin D. MacDonald, East Williston, N. Y., assignors to Sperry Rand Corporation, a corporation of Delaware

Application April 19, 1943, Serial No. 483,676

4 Claims. (Cl. 235—61.5)

This invention relates to a computing mechanism for gun sights of the "own speed" type.

The armament used on bombardment types of aircraft is usually designed primarily for defensive purposes, that is, to defend the craft against attacks by enemy craft that would prevent the bombardment craft from reaching its objective. The present invention is primarily directed to means for computing the lead angle by which the line of sight must be offset from the axis of the gun in order to effect a "hit" on the approaching enemy craft.

For guns located in the nose or tail of bombardment type aircraft it is possible to make certain assumptions in computing the lead angle. These assumptions are due, first, to the predetermined path normally followed by an attacking craft and, second, to the restricted cone within which an attacking craft approaches the nose or tail of a bomber. In order to fire at a bomber, an attacking enemy craft usually approaches a bomber in a manner such that its nose continuously points toward the bomber. If the bomber were not moving, the attacking craft would follow a straight line from its position at any given moment through the position of the bomber. Since the bomber is moving, the attacking craft follows a curved path in order to continuously point toward the bomber.

This path may be predetermined and is dependent upon the relative positions of the two crafts and the velocity of each. Since the attacking craft flies a predetermined course, its position after a given time of flight may be determined and the prediction angle between the line of sight and an imaginary line from the gun to the future position readily computed.

Once the prediction angle is ascertained, it is possible to determine the position at which the gun must be directed in order to fire a projectile toward the future position of the attacking aircraft. The path of the projectile is determined as the resultant of the aircraft's velocity and the muzzle velocity of the projectile.

Sights utilizing the factors just referred to are vector sights and are known by the Air Forces as "own speed" sights, and are thus distinguished from the more complicated sights using the angular rate—multiplied by time of flight solution.

The principle of the computer herein disclosed is to set up vectors mechanically representing the speed and direction of both the target and projectile. The arrangement in space of these two vectors gives the prediction angle.

One distinct advantage to be gained by the "own speed" method of computation is that the solution is instantaneous. There is no time lag and no amplification of tracking errors. The solution is complete whenever the sight is pointed at the target and there is no delay for tracking or settling. Even though accurate tracking is not necessary for the solution, it would be easier to accomplish than with other types of sights having disturbed reticles and using a rate multiplied by time solution. Sights of the type herein disclosed can be made very simple and

2

compact which is important where space and weight are at a premium.

One object of the invention is to provide an improved apparatus for computing the lead angle to increase the accuracy of aircraft gun sights.

Another object is to provide an improved apparatus for computing lead angle for aircraft gun sights used especially for defensive purposes.

A further object of the invention is to provide an apparatus for computing the lead angle due to the velocity of the plane on which the gun is mounted.

Other objects and advantages of the invention will become apparent from the following specification, taken in connection with the accompanying drawings, in which:

15 Fig. 1 is a perspective view of an aircraft gun showing a computing aircraft gun sight mounted on the gun.

Fig. 2 is a perspective view of a computing sight for use with a remote gun.

Fig. 3 is a schematic perspective view of the mechanism 20 used in the computing sights shown in Figs. 1 and 2.

Fig. 4 is a diagram showing the angular relations of the attacking and defending aircraft.

Fig. 5 is a space diagram showing relationships for computing azimuth and elevation components of the lead angle.

Fig. 6 is a flat schematic drawing which provides a simplified showing of a computer mechanism generally similar to that of Fig. 3.

30 Fig. 1 shows an aircraft gun designated generally at 1 supported by trunnions 2 which are rotatably mounted in a cradle 3 for providing movements of the gun 1 about a horizontal axis. The cradle 3 is rotatably mounted on a shaft 4 that is carried by a suitable pedestal 5 which may be attached to the body of the aircraft. A stationary

35 azimuth gear 6 is rigid with the pedestal 5, whereby movements of the cradle 3 and gun about the vertical axis of shaft 4 causes rotation of a pinion 7 carried by the cradle 3 in a manner to mesh with the azimuth gear 6. This pinion drives a flexible shaft 8 to supply data to computing mechanism 9 in accordance with the azimuth angle of the axis 11, 11 of the gun 1.

A gear sector 12, that is held rigidly mounted on the cradle 3, causes rotation of a pinion 13 which drives a shaft 14 to supply elevation data to the computing mechanism 9 as the gun is moved in elevation about the horizontal axis of trunnions 2.

40 Suitable hand grips 15 and 16 are provided for the operator to slew the gun to keep line of sight 17, 17 of sighting instrument 18 on a target such as an attacking aircraft.

45 Suitable knobs 21 and 22 are provided for introducing the indicated air speed and altitude, respectively, of the craft carrying gun 1 into the computing mechanism 9 to obtain a correction of indicated air speed for air density which amounts to setting into the computer a value or function of true air speed. Knobs 23 and 24 on the upper side of the computing mechanism 9 are connected with the sighting instrument 18 in a manner to align the line of sight 17 with the gun axis 11 by adjusting the azimuth

50 and elevation, respectively, of the line of sight.

60 Suitable knobs 21 and 22 are provided for introducing the indicated air speed and altitude, respectively, of the craft carrying gun 1 into the computing mechanism 9 to obtain a correction of indicated air speed for air density which amounts to setting into the computer a value or function of true air speed. Knobs 23 and 24 on the upper side of the computing mechanism 9 are connected with the sighting instrument 18 in a manner to align the line of sight 17 with the gun axis 11 by adjusting the azimuth and elevation, respectively, of the line of sight.

A preferred arrangement for introducing air speed and altitude is shown in Fig. 6. The device comprises an indicated air speed knob 21 fixed to a logarithmic scale 200 calibrated in miles per hour. The knob, when adjusted, drives an output shaft 128. Scale 200 cooperates with either of two lubber lines 201 and 202 marked on a ring or disc 203 mounted for rotation coaxially with respect to scale 200. An arm or knob 204 fixed to ring 203 is used 65 to position the lubber line being used with reference to a relatively fixed logarithmic scale or dial 205 calibrated in terms of altitude. Lubber line 201 is used when firing

at aircraft while rubber line 202 is used when strafing ground targets. In operation, the rubber line to be used is positioned opposite the appropriate point on the altitude scale and then dial 200 is adjusted by knob 21 to set the indicated air speed value on the dial opposite the rubber line. The multiple dial arrangement described is equivalent to a differential mechanism and when adjusted as described the output shaft 128 thereof is angularly displaced according to the logarithm of a function (Z) which will be referred to below.

Fig. 2 shows a remote gun 1' corresponding to the gun 1 of Fig. 1 and having an axis 11', 11'. The gun 1' is driven by suitable power mechanisms for directing the axis 11', 11' in accordance with the axis 25, 25 of computing mechanism 9' that is remote from the gun.

The computing mechanism is carried in a cradle 26 that is mounted on a shaft 27 which is rotatable in a brace 28 forming a part of the aircraft. Suitable trunnions 29 and 30 are provided for rotatably mounting the computing mechanism 9' in the cradle 26. A sector 12' engages a pinion 13' which rotates a shaft 14' in accordance with movements of the computing mechanism 9' in elevation about the horizontal axis of trunnions 29 and 30. Thus, the shaft 14' drives the elevation position of the axis 25 into the computing mechanism 9' in a manner similar to that which the shaft 14 drives gun elevation data into the computing mechanism 9. The axis 25 of the computing mechanism 9' is maintained coincident with the axis 11', 11' of the gun 1' in a manner subsequently to be explained.

The computing mechanism 9' has a line of sight 17', 17' defined by sighting instrument 18' corresponding to the line of sight and sighting instrument shown in Fig. 1. Knobs 23' and 24' are also provided for aligning the line of sight 17', 17' with the axis 25 of the computing mechanism 9'. Hand grips 15' and 16' correspond to the grips 15 and 16, and knobs 21' and 22' are provided for introducing indicated air speed and altitude of the aircraft into the computing mechanism 9'.

As the computing mechanism 9' is moved in azimuth with the vertical shaft 27, a gear 31 on the shaft 27 is rotated and drives a gear 32 which in turn drives a gear 33. Gears 32 and 33 drive through suitable shafts to position the rotors of coarse and fine electrical position transmitters 34 and 35 that are arranged to transmit the azimuth position of the axis 25 for the computing mechanism 9' to coarse and fine receivers 36 and 37, respectively, at the gun 1'. These receivers rotate the gun in azimuth by a gear 38 which is driven from gears 39 and 41, respectively, on the fine and coarse transmitters 37 and 36, respectively.

The elevation position of the axis 25 for the computing mechanism 9' is transmitted to the gun 1 by coarse and fine transmitters 42 and 43. The rotors of these transmitters are positioned in accordance with movements of the computing mechanism 9' about the horizontal axis of trunnions 29 and 30. A sector 44 is rotated with trunnion 30 and drives gears 45 and 46 to position the rotors of transmitters 42 and 43. The transmitters 42 and 43 supply elevation data of the axis 25 to receivers 47 and 48 which control the elevation position of the gun 1'. By suitably synchronizing the transmitters and receivers, the axis 11', 11' may be continuously positioned in accordance with the position of the axis 25 for the computing mechanism 9'.

As the gear 33 rotates in accordance with the azimuth position of the computing mechanism, a flexible shaft 8' is driven thereby to supply azimuth data to the computing mechanism 9' in a manner similar to that in which this data is supplied by the shaft 8 in Fig. 1.

Since the axis 11', 11' for the gun 1' is maintained coincident with the axis 25 for the computing mechanism 9', it will be apparent that the azimuth and elevation data supplied to the computing mechanism 9' by shafts 8' and 14' is equivalent to the azimuth and elevation position of the gun 1'.

The computing mechanisms 9 and 9' are substantially identical. Fig. 3 shows in detail the arrangement and co-operation of the various elements for the computing mechanism. Before describing the operation of the various elements in the computing mechanism, consideration will first be given to the problems involved in determining an accurate lead angle.

As shown in Fig. 4, an attacking craft 52 follows a pre-determined curved path 50 in order to continuously maintain its nose directed toward the position of defending craft 51 which is flying in the direction of a line 53 forming its longitudinal axis. During any given time of flight, the attacking craft 52 will move to a future position 52'. The prediction angle (α) is equal to the angle between line of sight 17 and the line connecting the original position of the defending craft 51 with the future position 52' of the attacking craft.

Considering the observed position 52 of the attacking aircraft as point A, the future position 52' as point B, and the location of the gun on the defending craft 51 as point C, it will be apparent that the prediction angle (α) may be computed from the relation of

$$\sin \alpha = \frac{S}{BC}$$

wherein S is the distance between the future position 52' and the line of sight to the present position 52. This distance S may be expressed as

$$S = \frac{V_p \omega T_p^2}{2}$$

wherein (V_p) is the velocity of the attacking aircraft 52, (ω) is the angular rate of turn of the pursuit craft at point A, and (T_p) is the time of flight of the projectile from the gun to the point B. The angular rate (ω) is a function of the velocity (V_p) of the defending craft 51, the angular position (θ_0) of the attacking craft, which is the angle of the line of sight 17 relative to the longitudinal axis 53 of the defending craft 51, and the range (D_0), which is the distance of the target 52 from the gun on the defending craft 51, and may be expressed as

$$\omega = \frac{V_b \sin \theta_0}{D_0}$$

Substituting the value of ω in the equation for the distance S we have

$$S = \frac{V_p V_b \sin \theta_0 T_p^2}{2 D_0}$$

and further substituting this value of S, the equation for the prediction angle α may be expressed as

$$\sin \alpha = \frac{V_p V_b \sin \theta_0 T_p^2}{2 D_0 BC}$$

Since the length of the line BC is the future range of the target, it may be approximated as the difference between the present range of the target (D_0) and the change in the present range during the time of flight of (T_p) which may be expressed as

$$\overline{BC} = D_0 - V_p T_p$$

Substituting this value for the line BC in the equation for the prediction angle (α) we have:

$$\sin \alpha = \frac{V_p V_b T_p^2}{2 D_0 (D_0 - V_p T_p)} \sin \theta_0 \quad (1)$$

As may be seen from Fig. 4, two forces act upon a projectile fired from a gun carried by the defending aircraft 51. These forces are due to the velocity (V_b) of the defending aircraft 51 and the muzzle velocity (V_m) of the projectile as it leaves the gun. In order to direct a projectile toward the future position 52', it is necessary to adjust the angle of the gun relative to the longitudinal axis 53 so the resultant effect of the muzzle velocity (V_m) and the velocity (V_b) of the defending craft

51 will be along the line connecting the gun and the future position 52'. The angle between the longitudinal axis 11 of the gun and the path of the projectile to the future position 52' may be referred to as a deflection angle (β) which is formed of two components, namely, the prediction angle (α) and a lead angle (λ) between the line of sight 17 and the gun axis 11. The lead angle between the line of sight and the axis of the gun is correctly determined when the gun is positioned in a manner such that the component of the velocity (V_b) of the defending craft across the line of fire is equal to the component of the muzzle velocity (V_m) across the line of fire. By equating these two components, we have

$$V_m \sin \beta = V_b \sin \theta_p$$

From an inspection of Fig. 4, it will be apparent that

$$\beta = \lambda + \alpha$$

and that

$$\theta_p = \theta_0 + \alpha$$

By substituting these values of (β) and (θ_p) we have:

$$\sin(\lambda + \alpha) = \frac{V_b}{V_m} \sin(\theta_0 + \alpha) \quad (2)$$

This may be written as

$$\sin \lambda \cos \alpha + \cos \lambda \sin \alpha = \frac{V_b}{V_m} (\sin \theta_0 \cos \alpha + \cos \theta_0 \sin \alpha) \quad (3)$$

Since the angles (α) and (λ) are always small, it can be assumed that their cosines are equal to unity, in which case Equation 3 may be written as

$$\sin \lambda + \sin \alpha = \frac{V_b}{V_m} (\sin \theta_0 + \cos \theta_0 \sin \alpha) \quad (4)$$

By combining Equations 1 and 4

$$\sin \lambda =$$

$$\left[\frac{1}{V_m} + \left(\frac{V_b}{V_m} \cos \theta_0 - 1 \right) \left(\frac{V_p T_p^2}{2D_0(D_0 - V_p T_p)} \right) \right] V_b \sin \theta_0 \quad (5)$$

This may be written as

$$\sin \lambda = \left[\frac{1}{V_m} + P \right] V_b \sin \theta_0 \quad (6)$$

where

$$P = \left[\left(\frac{V_b}{V_m} \cos \theta_0 - 1 \right) \left(\frac{V_p T_p^2}{2D_0(D_0 - V_p T_p)} \right) \right]$$

In Equation 6 it will be apparent that the reciprocal of the muzzle velocity

$$\left(\frac{1}{V_m} \right)$$

is a constant (K_1) for any particular gun. By plotting typical courses for the attacking craft, and assuming a time of flight, the value of P may be computed for various sets of circumstances depending upon the relative positions and the velocities of the respective crafts. The value of P is found to be small as compared with the constant (K_1) and varies over a fairly small range. For these reasons an average value of P may be selected and used as a constant (K_2). The constants (K_1) and (K_2) may be added to produce a gun constant (K). Using these assumptions, the lead angle (λ) may be computed from the equation

$$\sin \lambda = K V_b \sin \theta_0 \quad (7)$$

The expression ($K V_b$) is a function (Z) of the velocity of the defending aircraft. This function includes the effect of the velocity of the defending aircraft on the path of the attacking aircraft as well as its effect on the direction of a projectile fired from a gun. The function (Z) being a function of the aircraft's velocity may be computed as the product of functions of indicated airspeed and altitude. In the present invention, functions of in-

dicated airspeed and altitude are multiplied to obtain the function (Z) of the aircraft's velocity. This function is such that it includes consideration of the prediction angle (α) as well as a lead angle (λ) by which the line of sight must be offset relative to the axis of the gun in order to direct a projectile along a path displaced from the line of sight by the lead angle (λ).

In the foregoing description of the calculations necessary to ascertain the proper lead angle, the various angles 10 have all been considered in one plane. However, with gun mountings presently available and in conformance with present practices, it is necessary to introduce angles into the computing mechanism in terms of azimuth and elevation angles and, similarly, to compute the lead angle 15 in terms of azimuth and elevation components.

In other words, the present invention considers that a bullet fired from a gun on an airplane has two velocities imparted to it, the first being muzzle velocity and the second is due to the forward velocity of the airplane 20 supporting the gun. The path of the bullet to a stationary target is along the resultant vector of these two forces, generally speaking, and the computing mechanism solves for the elevation and azimuth components of this resultant vector. The forward velocity of the plane is multiplied by a constant to correct for the curved path of the pursuing plane which is the target, this being taken care of by suitably locating a lubber line, not shown, for the indicated air speed knob.

Fig. 5 shows in a space diagram the relations of these 30 various angles and the trigonometric constructions necessary in order to obtain azimuth and elevation components for them. By reference to this figure, it will be apparent that the azimuth and elevation position of the axis 11 for the gun represent the components of the difference angle ($\theta_0 - \lambda$), provided the azimuth angle is measured from the longitudinal axis 53 of the aircraft. Similarly, it will be apparent that angles (λ_a) and (λ_e) represent azimuth and elevation components of the lead angle (λ). In the 35 present computing sight, use is made of a reflex sight which utilizes azimuth and elevation components (λ'_a) and (λ'_e) to construct the lead angle (λ). For this reason, the following calculations are based on the assumption that (λ'_a) is equal to (λ_a). Further assuming that the 40 angles (λ_a) and (λ_e) are equal to their respective tangents, it may be shown from Fig. 5 that

$$\lambda'_a = \frac{Z}{1 - Z \cos A_e \cos E_e} \sin A_e \quad (8)$$

and that

$$\lambda'_e = \frac{Z}{1 - Z \cos A_e \cos E_e} \sin E_e \cos A_e \quad (9)$$

In order to compensate for the effect of gravity on the 55 projectile, it is necessary to subtract the gravity deflection angle (ϕ_s) from the elevation component angle (λ_e) of the lead angle (λ). The gravity deflection angle (ϕ_s) is a function of the range and the cosine of the gun elevation angle. By assuming an average range, the gravity 60 deflection angle may be computed as a constant multiplied by the cosine and the gun elevation angle (E_g). Therefore, the elevation difference angle ($\lambda_e - \phi_s$) may be expressed as

$$e = \frac{Z}{1 - Z \cos A_e \cos E_e} \sin E_e \cos A_e - K_3 \cos E_e \quad (10)$$

The details of computing mechanism 9 by which the 70 azimuth component (λ_a) of the lead angle (λ) and the elevation difference angle ($\lambda_e - \phi_s$) are determined from the gun azimuth and elevation angles together with values of indicated airspeed and altitude is shown clearly in Fig. 3. As previously described, computing mechanism 9 75 adjusts the line of sight 17 relative to the gun axis 11 in

accordance with azimuth component (λ'_a) of the lead angle and the elevation difference angle ($\lambda - \phi_s$).

The elevation angle of the gun is introduced into the mechanism by means of shaft 14 that is rotated by pinion 13 which meshes with the gear sector 12 and is thereby rotated by elevation movements of the gun. The gun azimuth angle is introduced by the flexible shaft 8 which drives a shaft 61 carrying pinion 62. Knobs 21 and 22 are used to introduce functions of indicated airspeed and altitude respectively. These knobs are positioned in accordance with scales on the casing of the computing mechanism 9. The scales are so arranged that shafts 63 and 64 are rotated in accordance with desired functions of indicated airspeed and altitude, depending upon the values used.

The line of sight is defined by an optical system including a source of light such as incandescent lamp 65. Rays from the source 65 pass through a glass having concentric circles marked thereon which form the reticle of the sight. These rays are then reflected by a mirror 67 on to an azimuth deflection mirror 68. Rays reflected from the azimuth deflection mirror 68 pass through a lens 69 onto elevation reflector 71 which is of the reflex type. The image of the reticle circles on glass 66 is thus superimposed on a target falling along the line of sight. Optical systems of this type are referred to as reflex sights and are well known in the art. It should be understood that other forms of sights may be used without departing from the present invention.

The manner in which the computing mechanism 9 utilizes gun azimuth and elevation angles and functions of altitude and indicated airspeed by solving Equations 9 and 10 to adjust the azimuth reflector 68 and the elevation reflector 71 will now be described. As has been described above, the function (Z) of the velocity of the aircraft 51 is the product of functions of indicated airspeed and altitude. Selected values of indicated airspeed and altitude as determined by instruments on the aircraft 51 are set into the mechanism 9 by arranging pointers on the knobs 21, 22 to correspond with the selected values as shown by the scales on the casing of the mechanism 9, for these pointers.

These scales are so arranged that the knobs 21 and 22 are rotated in accordance with logarithms of the desired functions of indicated airspeed and altitude respectively. It will be apparent therefore that the shaft 63 is rotated in accordance with a logarithm of the desired function of indicated airspeed. Similarly, the shaft 64 is rotated in accordance with the logarithm of the desired function of altitude.

The product of the functions of indicated airspeed and altitude is obtained by adding the two logarithms. This is accomplished by rotating input gears 72 and 73 of differential 74 in accordance with the logarithms of the desired function. Thus, the shaft 63 rotates a gear 75 which drives an idler gear 76 to rotate the input gear 72. The input gear 73 is driven by the shaft 64, pinion 77 and idler gear 78. Thus, by suitably selecting gearing ratios, output shaft 79 of the differential 74 is rotated in accordance with the logarithm of the product of the functions of the indicated airspeed and altitude, that is the logarithm of the function (Z) of the velocity of aircraft 51.

Shaft 14, which is rotated in accordance with the gun elevation angle, drives through suitable gearing 81 to rotate shaft 82 in accordance with the gun elevation angle (E_g). The shaft 82 drives through a pinion 83 to rotate a cam gear 84 on the periphery of cam disc 85 to rotate the cam disc in accordance with the gun elevation angle (E_g). Cam disc 85 has a cam groove 86 formed therein and so designed that a follower 87 having a cam pin 88 riding in the groove 86 will be displaced in accordance with the logarithm of the cosine of the gun elevation angle. This movement of the follower 87 rotates a shaft 89 carrying a pinion 91 which drives through a gear 92

to rotate shaft 93 and pinion 94 in accordance with the logarithm of the cosine of the gun elevation angle.

The produce of the function (Z) of the aircraft's velocity and the cosine of the gun elevation angle is obtained by adding the logarithms of these two functions. This addition is accomplished by differential 96, one input of which is driven by the shaft 79 in accordance with the logarithm of the function (Z). Input gear 95 of the differential 96 is rotated by the pinion 94 in accordance with the logarithm of the cosine of the gun elevation angle. Thus, output gear 97 of the differential 96 is rotated in accordance with logarithm of the product of the function (Z) and the cosine of the gun elevation angle (E_g).

15 This product is multiplied by the cosine of the gun azimuth angle by adding logarithms of these two factors. Input gear 98 of differential 99 is driven by the gear 97 in accordance with the logarithm of the product of the function (Z) multiplied by the cosine of the gun elevation angle. The other input gear 101 of differential 99 is rotated in accordance with the logarithm of the cosine of the gun azimuth angle in a manner which will now be described.

20 Pinion 62, which is rotated by shaft 8 in accordance with the gun azimuth angle, drives a gear 102 on shaft 103 that in turn drives pinion 104 in with a gear 105 on a periphery of cam 106 in accordance with the gun azimuth angle. A cam groove 107 formed in the surface of the cam disc 106 is so designed that a follower 108 having a pin 109 arranged to slide in the groove 107 is moved in accordance with the logarithm of the cosine of the gun azimuth angle. This movement of the follower 108 rotates the shaft 111 carrying a pinion 112 in accordance with said logarithm of the cosine of the gun azimuth angle.

35 The rotation of pinion 112 is utilized to drive through gear 113, shaft 114 and pinion 115 to rotate the input gear 101 of differential 99 in accordance with the logarithm of the cosine of the gun azimuth angle.

40 Thus, output shaft 116 of the differential 99 rotates a pinion 117 in accordance with the logarithm of the product of the function (Z) of the aircraft velocity, cosine of the elevation angle and cosine of the azimuth angle. This may be represented by the expression

$$\text{Log} (Z \cos E_g \cos A_g)$$

45 By subtracting this expression from unity, it will be apparent that the denominator of the expressions for the azimuth and elevation components of the lead angle as set forth in Equations 8 and 9 will be obtained. To accomplish this, pinion 117 drives gear 118, shaft 119 and pinion 121 in accordance with the above expression. Pinion 121 meshes with a gear 122 on the periphery of cam disc 123. It has a cam groove 124 formed on the surface thereof whereby a follower 125 carrying a cam pin 126 is displaced in accordance with the expression

$$\text{Log} (1 - Z \cos E_g \cos A_g)$$

50 In order to divide this expression into the function (Z) of the aircraft's velocity, the logarithm of the expression is subtracted from the logarithm of the function (Z) by a differential 127. Input shaft 128 of the differential 127 is driven by shaft 79 which is rotated in accordance with the logarithm of the function (Z) of the aircraft's velocity. Input gear 131 of the differential 127 is driven in accordance with

$$\text{Log} (1 - Z \cos E_g \cos A_g)$$

55 by a pinion 132 on shaft 133 which is rotated in accordance with the above expression by the cam follower 125.

70 As may be seen in Fig. 3, pinion 132 drives through a gear 134 on shaft 135 and pinion 136 to rotate the gear 131 in accordance with the expression.

The gearing and gear ratios are so arranged that the input of the differential 127 represented by the gear 131 is subtracted from the input of the differential 127 repre-

sented by the shaft 128. Thus, the two inputs are subtracted and output gear 137 is driven in accordance with the expression

$$\text{Log} \left(\frac{Z}{1-Z \cos E_g \cos A_g} \right)$$

It may be seen from the Equation 8 that the azimuth component (λ'_a) of the lead angle (λ) is equal to the product of the above expression and the sine of the gun azimuth angle. This product is obtained from a three-dimensional cam 141 which is translated in accordance with the above expression and rotated in accordance with the gun azimuth angle (A_g). Translation of the cam 141 is effected by a pinion 142 that meshes with a cylindrical rack 143. The pinion 142 is driven by gear 144 on shaft 145 that meshes with the output gear 137. Thus, the pinion 142 is rotated and translates cam 141 in accordance with the expression

$$\text{Log} \left(\frac{Z}{1-Z \cos E_g \cos A_g} \right)$$

Shaft 103 drives through suitable gearing 146 to rotate shaft 147 and elongated pinion 148 in accordance with the gun azimuth angle (A_g). The pinion 148 meshes with the gear 149 to rotate the cam 141 in accordance with the gun azimuth angle. The surface of the three-dimensional cam 141 is so designed that cam follower 151 riding thereon is translated in accordance with the azimuth component (λ'_a) of the lead angle (λ) as determined by Equation 8. Cam follower 151 has a worm 152 on one end arranged to engage a worm gear 153 whereby shaft 154 rotates the azimuth reflector 68 in accordance with the azimuth component of the lead angle.

As may be seen from Equation 9 the elevation component (λ_e) of the lead angle (λ) is equal to the product of the expression

$$\left(\frac{Z}{1-Z \cos A_g \cos E_g} \right)$$

by which the cam 141 is translated, the sine of the gun elevation angle (E_g) and the cosine of the gun azimuth angle (A_g). Since the cam 141 is translated in accordance with the above expression and rotated in accordance with the gun azimuth angle, it is evident that a follower 157 angularly displaced by 90° with respect to the follower 151 is moved in accordance with the expression

$$\left(\frac{Z}{1-Z \cos A_g \cos E_g} \right) \cos A_g$$

This expression is multiplied by the sine of the gun elevation angle (E_g) by a three-dimensional cam 158 that is translated by cam follower 157 in accordance with the above expression and rotated by an elongated pinion 159 on the shaft 82. Since the shaft 82 is rotated in accordance with the gun elevation angle (E_g), the elongated pinion meshing with a gear 161 on the cam 158 rotates the cam 158 in accordance with the gun elevation angle. The cam 158 may be laid out in a manner such that the cam follower 162 riding on the surface thereof is translated in accordance with the elevation component (λ_e) of the lead angle as defined by Equation 9.

Since the line of sight 17 is offset vertically with respect to the gun axis 11 in accordance with the elevation component of the lead angle, it is necessary to reduce the amount of this offset angle by the gravity deflection angle (ϕ_s) that is the angle by which a projectile fired from the gun is deflected from a line representing the gun axis due to the force of gravity. As previously explained, this deflection angle is a function of the range and the gun elevation angle.

However, since an average range may be used, the gravity deflection angle (ϕ_s) may be determined by multiplying the cosine of the gun elevation angle by a suitable constant. This deflection angle is therefore a function

of the gun elevation angle and its value may be subtracted from the surface of the cam 158. Thus, the surface of the cam 158 is actually laid out in a manner such that the follower 162 is translated in accordance with the elevation difference angle ($\lambda_e - \phi_s$) where the gravity deflection angle (ϕ_s) is determined as the product of a constant in the cosine of the gun elevation angle.

5 A worm 163 on the cam follower 162 engages a worm gear 164 on shaft 165 to rotate the elevation reflector 71 in accordance with the elevation difference angle.

10 Since the azimuth and elevation reflectors 68 and 71 are adjusted in accordance with the azimuth component (λ'_a) of the lead angle and the elevation difference angle ($\lambda_e - \phi_s$) as determined by Equations 8 and 10, the line of sight 17 is offset with respect to the gun axis 11 by these angles. A projectile fired from the gun will, therefore, follow approximately the path displaced by the prediction angle (α) from the line of sight at the instant that the projectile is fired. The function (Z) of the defending aircraft's velocity, as used in determining the azimuth and elevation components of the lead angle, makes allowance for the deviation of the attacking craft from the line of sight. The path of a projectile fired from the gun will deviate from the line of sight 17 by an amount corresponding to deviation of the attacking craft 52. Obviously, the amount of this deviation is dependent to some extent upon range. However, it has been determined that accurate results may be obtained by using an average value of range in the computations of the lead angle.

since suitable transmission systems are utilized to maintain the axis 11', 11' of the gun 1' coincident with the axis 25 of the computing mechanism 9', the shafts 8' and 14' are rotated substantially in accordance with the azimuth and elevation angles of the gun.

As previously explained, the computing mechanism and gun sight herein described is primarily for use on aircraft in defense against attacking aircraft. Although the gun has been described as being used on a bomber, it should be understood that it may be used on any type of aircraft without departing from the invention. The best results may be obtained by using this sight and computing mechanism in the tail or nose of a defending craft because some of the approximations are based upon the conditions existing in firing at targets located within the tail or nose cone of the craft.

Equations 8 and 9 represent computations for the azimuth and elevation component lead angles for the tail cone of the aircraft. As has been explained, the invention may be used in either the tail or the nose of the craft. For the nose cone, Equations 8 and 9 must be revised.

From Equation 7 it is apparent that the lead angle (λ) is dependent upon the sine of the sighting angle (θ_0). However, the mechanism is supplied with the position angles of the axis of the gun. For a gun in the tail of the craft, the gun position angle is equal to the difference between the sighting angle (θ_0) and the lead angle (λ), whereas the position angle of a gun in the nose is equal to the sum of the sighting angle (θ_0) and the lead angle (λ).

Equations 8 and 9 automatically compensate for this change in the relationship of the gun position angles and the sighting angle if the gun position angles are measured from the tail of the craft in both instances. As the gun azimuth angle (A_g), for example, exceeds 90° , the cosine of this angle becomes the cosine $(180 - A_g)$ or a negative value. However, the mechanism 9 uses a logarithmic solution for Equations 8, 9 and 10 thus making it impossible to use the cosine function of angles greater than 90° .

In order to use the mechanism for a gun in the nose of the aircraft, it is necessary to change the negative (-) sign in the denominator of Equations 8, 9 and 10. For a gun in the nose, these equations are written as

$$\lambda' a = \frac{Z}{1 + Z \cos A_s \cos E_s} \sin A_s \quad (11)$$

$$\lambda_e = \frac{Z}{1 + Z \cos A_e \cos E_e} \sin E_e \cos A_e \quad (12)$$

$$(\lambda_c - \phi_s) = \frac{Z}{1 + Z \cos A_s \cos E_s} \sin E_s \cos A_s - K_3 \cos E_s \quad (13)$$

The mechanism is changed to solve Equations 12 and 13 by changing the cam groove 124 in disc 123 so the follower 125 is displaced in accordance with the expression

$$\log (1+Z \cos E_g \cos A_g)$$

Since for a gun in the nose of the aircraft, the azimuth component lead angle (λ_n) and the elevation difference angle ($\lambda_e - \phi_s$) are subtracted from the gun position angle to determine the line of sight, it is necessary that the reflectors 68 and 71 be moved to subtract these angles instead of adding them to the gun position angles as is the case for a gun in the tail of the craft. This subtraction may be accomplished by designing cam 141 to have negative lifts, so that followers 151 and 157 will be displaced to move the line of sight in the opposite direction to that in which it is moved for a tail gun.

It will be obvious to those skilled in the art that the computing mechanism and gun sight described may also be used with great accuracy in firing from an aircraft.

toward relatively stationary targets, such as targets on the ground or comparatively slowly moving targets in the air.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. In an automatic computing mechanism for a gun sight of the "own speed" type for aircraft, the combination of azimuth and elevation members movable respectively in accordance with the azimuth and elevation movements of a gun on the aircraft, means to convert the movement of the azimuth member to a movement representing the logarithm of a cosine function of gun azimuth, means to convert the movement of the elevation member to a movement representing the logarithm of a cosine function of gun elevation, means settable according to the indicated air speed and altitude of the aircraft to represent the logarithm of a function of the air velocity of the aircraft, means to combine the logarithmic representations, means to convert the combined logarithmic representation to a representation of the logarithm of unity minus the combined logarithmic representation, means to subtract the last recited logarithmic representation from the representation of the logarithm of the function of air velocity, and means to multiply the quantity represented by the resulting logarithm by the sine of gun azimuth.
  2. In an automatic computing mechanism for a gun sight of the "own speed" type for aircraft, the combination of azimuth and elevation members movable respectively in accordance with the azimuth and elevation movements of a gun on the aircraft, means to convert the movement of the azimuth member to a movement representing the logarithm of a cosine function of gun azimuth, means to convert the movement of the elevation member to a movement representing the logarithm of a cosine function of gun elevation, means settable according to the indicated air speed and altitude of the aircraft to represent the logarithm of a function of the air velocity of the aircraft, means to combine the logarithmic representations, means to convert the combined logarithmic representation to a representation of the logarithm of unity minus the combined logarithmic representation, means to subtract the last recited logarithmic representation from the representation of the logarithm of the function of air velocity, means to multiply the quantity represented by the resulting logarithm by the cosine of gun azimuth, and means to multiply the resulting product by the sine of gun elevation.
  3. In an automatic computing mechanism for a gun sight of the "own speed" type for aircraft, the combination of azimuth and elevation members movable respectively in accordance with the azimuth and elevation movements of a gun on the aircraft, means to convert the movement of the azimuth member to a movement representing the logarithm of a cosine function of gun azimuth, means to convert the movement of the elevation member to a movement representing the logarithm of a cosine function of gun elevation, means settable according to the indicated air speed and altitude of the aircraft to represent the logarithm of a function of the air velocity of the aircraft, means to combine the logarithmic representations, means to convert the combined logarithmic representation to a representation of the logarithm of unity plus the combined logarithmic representation, means to subtract the last recited logarithmic representation from the representation of the logarithm of the function of air velocity, and means to multiply the quantity represented by the resulting logarithm by the sine of gun azimuth.

4. In an automatic computing mechanism for a gun sight of the "own speed" type for aircraft, the combination of azimuth and elevation members movable respectively in accordance with the azimuth and elevation movements of a gun on the aircraft, means to convert the movement of the azimuth member to a movement representing the logarithm of a cosine function of gun azimuth, means to convert the movement of the elevation member to a movement representing the logarithm of a cosine function of gun elevation, means settable according to the indicated air speed and altitude of the aircraft to represent the logarithm of a function of the air velocity of the aircraft, means to combine the logarithmic representations, means to convert the combined logarithmic representation to a representation of the logarithm of unity plus the combined logarithmic representation, means to subtract the last recited logarithmic representation

from the representation of the logarithm of the function of air velocity, means to multiply the quantity represented by the resulting logarithm by the cosine of gun azimuth, and means to multiply the resulting product by the sine of gun elevation.
